UNITED STATES PATENT OFFICE.

F. E. OLIVER, OF NEW YORK, N. Y.

COMBINED PAPER-CUTTER AND RULE.

Specification of Letters Patent No. 31,556, dated February 26, 1861.

To all whom it may concern:

Be it known that I, F. E. OLIVER, of New York, in the county of New York and State of New York, have invented a Combined 5 Paper-Cutter and Rule, the same forming a new and useful article of manufacture and instrument or implement of a character never before known or used; and I do hereby declare that the following, taken in connection with the accompanying drawing, which forms part of this specification, is such a full and clear description of my invention as to enable others to make and use the same.

In banks and private or public offices and 15 other places or establishments, where the paper cutter or tearer and round rule or ruler are, if not indispensable, at least most convenient appendages to the desk or table, it is no small annoyance, when requiring to 20 use first the one of these devices and then the other (as for instance in ruling and tearing off bank checks or drafts), to find that on laying down the one to take up the other the latter is not to be found or difficult of reach 25 without moving from one place to another. This involves loss of time, which in business is important. Such however is not the only annoyance or inconvenience which attaches to the use of these devices as they are ordinarily 30 constructed and as separate implements or articles. The ordinary paper cutter or tearer is simply a flat sheet or blade of tin, hard rubber or other suitable material, made very thin and usually of oblong form, 35 with its edges straight and its ends or one of them of irregular shape with an aperture through it to facilitate handling of the article or for suspending it on a nail or other projection. Such form or construction does 40 not present a ready surface for taking up off a table or desk said cutter with despatch and it being but a thin flat strip it not unfrequently gets mixed up with and under papers on the desk so that when wanted the 45 same is difficult to be found. Likewise as regards the round rule or ruler, which in avoiding blotting or blurring and forming a more eligible guiding surface for the pen than is the case with a thick flat ruler; said 50 ruler which is ordinarily constructed of wood or rubber, is not only liable to roll off the desk by reason of the usual inclined surface of the latter, so that when laying down the ruler it is difficult to locate it with certainty 55 as to its remaining where placed, but also, when using said ruler, there is great

risk of it shifting or moving from the position in which it is set by reason of its round configuration not presenting a firm or steady bearing on the paper or book. All of 60 these objections, annoyances or inconveniences are avoided by my novel combination of flat paper cutter with a round or raised and rounded edge ruler in the one implement, and certain advantages obtained or 65 capable of being obtained by it, which are not incidental to the two devices separately considered.

Referring to the accompanying drawing, Figures 1 and 2 represent two forms, in perspective, of my paper cutter and round edged ruler combined; Fig. 3 a longitudinal section through the ruler portion of the implement as shown in Fig. 1; and Fig. 4 a transverse section of the same in direction of 75 the line *c, d*, in Fig. 1.

In the figures, A denotes the paper cutter which may be made of metal plain or japanned, hard rubber or any other suitable material and of any desired length and 80 width, the same constituting a thin and flat blade or strip the one edge (*a*) of which serves as the guiding and cutting surface by tearing the paper along it as well understood. The ends of said strip or cutter may 85 be either straight or of irregular form, as shown in Figs. 1 and 2, but I prefer to make them straight as consuming less metal and labor. Holes (*b*) may be made near either or both of their ends, or in the middle of the 90 strip, to provide for hanging it up when not in use. On the opposite edge of said strip to that which forms the cutting surface, I arrange the raised and round edged ruler (B) which may either be separately attached to 95 the strip or be formed out of it by turning or bending the edge over as shown in Figs. 1, 2 and 4. Said ruler may be made of any suitable material. I prefer that it should project above only the one side or flat surface of the cutting strip so that the latter may lie flat on the paper it is used to tear or cut. Whatever the configuration of the upper or inside edge of said ruler, its outside edge or surface which guides the pen 100 and is the ruling edge should be rounded. In this way I combine a thin paper cutter and thick round or round-edged ruler in the one implement, whereby both of these devices may be used alternately or in succession with despatch, the round or round-edged ruler is restrained by the flat strip to which 105 110

it is attached or of which it forms part from 5
rolling off the desk or out of place, and when
set to rule a line is held steady to its place
by the flat strip; also whereby the raised
portion which forms the ruler serves as a
handle to facilitate the lifting of the paper
cutter from the desk and makes it less liable
to be concealed by papers on the desk. But
valuable as is such a combination, this is not
10 or need not be all. Thus, the ruler portion
(B) of the implement, may, if preferred, in-
stead of being made solid, be formed hollow,
as shown in the drawing, so as to constitute
15 a receptacle for paper in small roll or for
pencil or pen or all of these. As a pen or
pencil depository it will be found very con-
venient and to prevent injury to the nib of
the pen or point of the pencil, likewise to
enlarge yet further the utility of the imple-
20 ment, the ends of such hollow ruler may be
stopped by plugs (c) of india rubber the
one or both of which may project and is
fitted so as to be capable of being withdrawn
to admit of the removal of the pen or pencil
25 and so that said rubber plug may be used as
an eraser. The plugs however need only be

faced with rubber, or where only one of
them is designed to withdraw and to act as
an eraser, the other may be of any suitable
material or construction presenting a soft 30
inner end to protect the point of the pen or
pencil as before specified. In this way
many necessary articles used by clerks and
others may be combined in the one imple-
35 ment for portable use in a small space or
compass and compact shape or form.

Having now described my invention, I
claim—

A combined paper cutter and ruler having
for its peculiar characteristic a paper cut- 40
ting or tearing blade and, on the opposite
edge of the implement to that which forms
the cutting edge, a raised and round or
round edged ruler made either hollow or
solid substantially as herein set forth. 45

In testimony whereof I have signed my
name to this specification before two sub-
scribing witnesses.

F. E. OLIVER.
